(57) **CLAIM**

The ornamental design for a display screen or portion thereof with a graphical user interface, as shown and described.

DESCRIPTION

FIGURE is a first image of a display screen or portion thereof with a graphical user interface in accordance with the present invention.

The broken lines in the FIGURE are for the purpose of illustrating environmental structure and portions of the display screen or portion thereof with graphical user interface that form no part of the claimed design.

1 Claim, 1 Drawing Sheet
